W. A. CAMPBELL,
WIRE STRETCHER,
APPLICATION FILED FEB. 21, 1918.

1,273,456.

Patented July 23, 1918.

UNITED STATES PATENT OFFICE.

WILBER ALLEN CAMPBELL, OF FLORA, ILLINOIS.

WIRE-STRETCHER.

1,273,456.

Specification of Letters Patent. Patented July 23, 1918.

Application filed February 21, 1918. Serial No. 218,496.

To all whom it may concern:

Be it known that I, WILBER ALLEN CAMPBELL, a citizen of the United States, and a resident of Flora, in the county of Clay 5 and State of Illinois, have invented certain new and useful Improvements in Wire-Stretchers, of which the following is a specification.

My invention is an improvement in wire stretchers, and has for its object to provide a device of the character specified for erecting and stretching woven wire and single strand fence wire with ease and rapidity, and wherein a series of grips is provided for 15 engaging the wire, together with means for simultaneously making tension on the grips to tighten the wire.

In the drawings:

Figure 1 is a front view of the device in

20 use;

Figs. 2 and 4 are sections on the lines 2—2 and 4—4, respectively, of Fig. 1;

Fig. 3 is a front view of the handled nut;

Fig. 5 is a perspective view of the sleeve.

25 In the present embodiment of the invention, a series of grips is provided, each consisting of a pair of crossed members 1 and 2 pivotally connected, as indicated at 3, and having looped handles 4 which are connected by a flexible member 5, as, for instance, a chain, to a stretcher bar 6. The arrangement of the handles is such that the greater the pull upon the handles the tighter the gripping jaws will be clamped upon the 35 wire.

The stretcher bar 6 has an opening at each grip, and the chain 5 of each grip engages the adjacent opening. The end opening and the central opening of the stretcher bar have 40 flexible members 7 and 8 connected therewith, and these flexible members at the ends remote from the stretcher bar are connected to a common ring 9. To this ring is connected a draw screw 10, by means of a hook 45 11 at one end of the screw. This screw, as shown in Figs. 1 and 2, is composed of four bars arranged in spaced parallel relation, the outer faces of the bars being threaded,

and the screw is passed through a guide sleeve 12 which has a square bore, and 50 grooves 13 in the faces of the bore for receiving the individual bars of the screw. Thus while the screw can move longitudinally of the guide sleeve it cannot rotate with respect to the sleeve. 55

The guide sleeve has a radial arm 14 at one end, and a chain 15 is connected with the other end of the sleeve, being connected to a perforated lug 16 on the sleeve. The arm 14 has a notch, as shown, for engagement by the chain to secure the guide sleeve to a post 17 or other fixed support. A nut 18 is threaded on to the draw screw at the end of the sleeve remote from the hook 11, and this nut has oppositely extending handle members 19 for convenience in turning the same.

Referring to Figs. 1 and 4, it will be noticed that the gripping faces of the jaws 1 and 2 are corrugated, and that the jaw 1 70 fits within the jaw 2, the jaw 2 being channel shaped to receive the jaw 1. With this arrangement there is no possibility of the wire 20 becoming disengaged from the jaws.

It will be noticed that each wire grip is 75 provided at the top with a cutting device for cutting wire. The handles of the handled nut are tubular or hollow, for the purpose of permitting engagement by a lever.

I claim:

In a device of the character specified, a draw screw and a guide sleeve for the screw having means for connecting the sleeve to a post or other fixed support, said draw screw consisting of four sections arranged about a 85 common axis and externally threaded and connected at their ends to each other, the sleeve having grooves for receiving the sections, and a handled nut threaded on to one end of the draw screw, the other end having 90 means for engaging the objects to be moved.

WILBER ALLEN CAMPBELL.

Witnesses:
